SHOE HEELING MACHINE

Walter Aeschbach and Audry C. Ray, St. Louis, Mo., assignors, by mesne assignments, to Cool-Moore Corporation, St. Louis, Mo., a corporation of Missouri

Application February 23, 1939, Serial No. 257,838

17 Claims. (Cl. 12—42)

This invention relates generally to shoe machines and more specifically to an improved machine adopted for use in attaching high heels to women's shoes with the aid of heel attaching devices of the type covered by United States Letters Patent No. 2,004,979, granted to David E. Cool on June 18, 1935, the predominant object of the invention being to provide a machine of this type which is intended to perform the same function as the machine covered by United States Letters Patent No. 2,144,143, granted to the said David E. Cool on January 17, 1939, but which includes improved details of construction and arrangement.

15 The heel attaching device covered by United States Letters Patent No. 2,004,979 referred to above, comprises a hollow element in the form of a sleeve which is provided at one end with a flange and at its opposite end with a plurality of 20 displaceable portions, said displaceable portions being provided with inwardly curved faces in contact with which a suitable tool is moved to spread the displaceable portions outwardly. In applying the heel attaching device to a shoe a 25 hole is formed through the insole of the shoe and in the heel to be attached thereto and the heel attaching device is introduced into these holes. In its final heel-securing position in the shoe the flange of the heel attaching device is 30 countersunk in the insole of the shoe, and the displaceable portions of the heel attaching device are spread outwardly so that they bite into the material of the heel and in this manner secure the heel to the shoe.

35 The improved machine as disclosed herein includes as an important feature thereof an indexing mechanism which carries a plurality of drills and a plurality of punches, said indexing mechanism being arranged for rotary movement 40 and straight line movement so that in the operation of the machine the indexing mechanism is rotated to properly position a drill and is then moved in a straight line to perform the drilling operation, and thereafter the indexing mechanism 45 is rotated to properly position a punch which supports a heel fastening device and is then moved in a straight line to cause the punch to introduce the heel fastening device into the hole in the insole and heel of the shoe previously 50 formed by a drill and spread the displaceable portions of the heel fastening devices to secure the heel to the shoe.

The improved machine disclosed herein includes other important unique features among 55 which is an improved feeding mechanism for

feeding the heel fastening devices to the punches of the indexing mechanism, and improved means for properly locating with respect to the machine the lasts on which are supported the shoes being operated on by the machine. All of the 5 features mentioned are described in detail in the following specification and are illustrated in the drawings in which:

Fig. 1 is a view of the improved machine showing same partly in side elevation and partly in 10 vertical section.

Fig. 2 is an enlarged, fragmentary section illustrating the indexing mechanism of the machine together with the means for operating same and for actuating the drills associated with the 15 indexing mechanism.

Fig. 3 is a fragmentary elevation of mechanism illustrated in Fig. 2 which serves to rotate the indexing mechanism.

Fig. 4 is an enlarged horizontal section taken 20 on the line 4—4 of Fig. 2.

Fig. 5 is a horizontal section taken on line 5—5 of Fig. 2.

Fig. 6 is a cross-section taken on line 6—6 of 25 Fig. 2.

Fig. 7 is a view of the machine shown partly in front elevation and partly in vertical section.

Fig. 8 is a fragmentary plan view illustrating the mechanism for adjusting the lasts, on which the shoes being operated on are supported, to 30 their proper elevations.

Fig. 9 is an enlarged fragmentary vertical section taken on line 9—9 of Fig. 8.

Fig. 10 is a fragmentary front elevation illustrating portions of the indexing mechanism and 35 the fastener feeding mechanism of the machine.

Fig. 11 is a view similar to Fig. 10 but illustrating the indexing mechanism of the machine in a changed position.

Fig. 12 is a fragmentary side elevation of part 40 of the mechanism illustrated in Figs. 10 and 11.

Fig. 13 is a view similar to Fig. 12 but showing the illustrated parts of the machine in changed positions.

Fig. 14 is a cross-section on an enlarged scale 45 of the hold-down mechanism for holding a heel in position with respect to a shoe being operated on by the machine.

Fig. 15 is a horizontal section taken on line 15—15 of Fig. 13.

Fig. 16 is a fragmentary sectional view illustrating the step of drilling a hole through the insole and in the heel of a shoe during the operation of the machine.

Fig. 17 is a view similar to Fig. 16 but showing 55

the condition after the drilling operation has been completed and as a fastening element is about to be introduced into place in the previously drilled hole through the insole and in the heel of the shoe.

- 10 Fig. 18 is a view similar to Fig. 17 but showing the fastening element after it has been arranged in the hole in the insole and heel of the shoe.
- 15 10 Fig. 19 is a view similar to Fig. 18 but showing the displaceable portions of the heel fastening element after they have been spread by a punch of the machine.

- 15 Fig. 20 is a perspective of one of the heel fastening elements with which the machine is operable.

20 In the drawings, wherein is shown for the purpose of illustration, merely, one embodiment of the invention 1 designates the main frame 20 of the machine, said main frame comprising a top plate 2 with which suitable legs 3 are associated. The top plate 2 is preferably, though not necessarily, rectangular in shape when viewed in plan, and if desired plates 4 may be secured 25 to the legs 3 at the four sides of the main frame to enclose the mechanism disposed beneath the top plate of the main frame. At the lower portion of the main frame 1 a base plate 5 is secured at its opposite ends to brackets 6 secured to the 30 legs of the main frame, said base plate serving to support mechanism of the machine which will now be described.

35 Supported by and secured to the base plate 5 is an electric motor 7 with which is associated a short shaft 8 (Figs. 1 and 5), said shaft being suitably supported for rotation. The motor 7 has associated therewith a gear housing 9 which encloses suitable gearing (not shown) for transmitting rotary motion from the main shaft of 40 the motor to the shaft 8. Fixed to the end of the shaft 8, opposite to the end thereof at which the motor 7 is located, is a clutch element 10 as shown to the best advantage in Fig. 5.

45 Alined longitudinally with the short shaft 8 is a longer shaft 11 which is supported for rotation by a pair of spaced bearings 12 and 13, said bearings being supported by and secured to the base plate 5. At the end of the shaft 11 located adjacent to the short shaft 8 said shaft 11 has 50 mounted thereon for sliding movement longitudinally of said shaft a clutch member 14, said clutch member as will presently appear herein being adapted for sliding movement with respect to the shaft 11 into and out of clutching engagement with the clutch member 10 of the shaft 8. The clutch member 14 is provided with an annular groove 15 formed therein and associated therewith and preferably forming an integral part thereof is a pinion 16. The structure comprising the clutch member 14 and the pinion 16 is preferably splined to the shaft 11 so that while said structure may move longitudinally of the shaft it rotates at all times with said shaft 11. Interposed between an end face of the bearing 12 and a face of the pinion 16 is a coil spring 17 which tends to expand and thereby move the clutch member 14 into clutching engagement with the clutch member 10 of the shaft 8.

55 Supported by a bearing 18 extended from the bearing 12 and a bearing 19 supported by the base plate 5 is a short shaft 20 which has fixedly mounted thereon a gear wheel 21 which meshes with the pinion 16 of the shaft 11. The pinion 16 and gear wheel 21 are geared two to one so 60 that the shaft 20 will rotate one complete revolution while the shaft 11 is making two complete revolutions. In order to hold the clutch member 14 out of clutching engagement with respect to the clutch member 10 and to permit the coil spring 17 to move said clutch member 14 into 5

clutching engagement relative to said clutch member 10 during certain phases of the operation of the machine, a mechanism is provided which includes a vertical arm 22 which is pivotally secured at its lower end, as shown at 23 in Fig. 1, to an element 24 which is pivoted at 24' to a member 24^a fixed to the base plate 5. At its upper end the arm 22 is loosely connected to a horizontal arm 25 (Fig. 7) and this arm 25 is loosely connected at its opposite end to an operating element 26 which is pivoted at 27 to a bracket 28 which is fixed to the main frame of the machine.

20 The operating element 26 has associated with it a coil spring 29 which is connected at its opposite ends to said operating element and a bracket 30 secured to the main frame of the machine. The element 24 has mounted thereon a rotary roller 31 which extends into the annular groove 15 of the clutch member 14 as shown in Fig. 5. 25 The shaft 20 has fixedly mounted thereon a cam 32 which is provided with a high spot 32' and when the machine is not operating the high spot of the cam 32 contacts with a side face of the vertical arm 22 as shown in Fig. 5. When, however, it is desired to cause the clutch member 14 of the shaft 11 to move into clutching engagement with the clutch member 10 of the shaft 8, the operating element 26 is operated to move the improved end of the vertical arm 22 in the direction indicated by the arrow in Fig. 7. This movement of the vertical arm 22 will move the portion of said arm with which the high spot of the cam 32 movably contacts out of contact with said high spot, thereby permitting the coil spring 30 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 wardly to disengage the clutch member 14 from the clutch member 10 and arrest movement of the shafts 11 and 20.

Secured to the top plate 2 of the main frame 1 of the machine at the lower face of said top plate is a guide 33 which extends downwardly from said top plate and is shaped in cross-section as shown in Fig. 4. In other words the guide 33 is provided with an opening 34 formed longitudinally thereof and the portions of the guide at opposite sides of the opening 34 are provided with dove-tail grooves 35 as shown in Fig. 4. Supported by the guide 33 for vertical movement with respect thereto is an indexing mechanism 36, said indexing mechanism including a supporting member 37 which is provided at its opposite sides with portions 38 (Fig. 4) that are shaped to fit in the dove-tail grooves 35 of the guide 33. The portions 38 are guided for vertical movement by the walls of the grooves 35 of the guide 33 and because of the dove-tail shape of said grooves lateral displacement of the portions 38 from the grooves is prevented. The supporting member includes also an elongated integral sleeve 39 which extends through the opening 34 of the guide 33 and beyond said guide. At its lower end the supporting member 37 is provided with a bifurcated portion 40 between the spaced legs of which the upper end portion of a connecting rod 41 is pivotably connected by a pin 42, the lower end portion of said connecting rod being connected to a crank 43 which forms a part of the shaft 11. In view of the arrangement just described it is obvious that rotation of the shaft 11 will impart vertical reciprocatory movement to the supporting member 37 with respect to the guide 33, the sleeve 39 of said supporting member during such reciprocatory movement moving longitudinally of the opening 34 of the guide.

The sleeve 39 of the supporting member 37 receives therein a sleeve 44 which is provided at one end with head 45, said head being provided with a cavity 46 formed therein which is closed by a removable cover plate 47 that is provided with an outwardly extended, screwthreaded shank 48. As will presently appear herein, the sleeve 44 is rotated within the sleeve 39 and therefore bushings 49 are provided to facilitate such rotation. By referring to Fig. 2 it will be noted that the head 45 of the indexing mechanism 36 is provided with opposed and alined screw-threaded openings 50, and each of these openings receives the reduced, externally screwthreaded, inner end 55 of a cylindrical housing 51. Each cylindrical housing is closed at its outer end by a cap 52 which screwthreadedly engages the outer end portion of the associated housing as shown in Fig. 2, and each cap is provided with a central opening in which a bushing 53 is arranged. Supported by each cylindrical housing is a sleeve 54 which is supported for sliding movement within the associated bushing 53 longitudinally thereof, each sleeve 54 being provided with a flange 55 at its inner end which is located within the associated cylindrical housing and is of only slightly less diameter than the interior of said cylindrical housing. Arranged within each of said cylindrical housings is a coil spring 56 which contacts at its opposite ends with a wall of the housing and the flange of the associated sleeve 54. Because of this arrangement the sleeves are normally moved to the limit of their outward movement with respect to the housings 51 by the coil springs, such outward limit of movement being

established by the flanges of the sleeves contacting with the inner faces of the caps 52. However the sleeves 54 may be moved inwardly relative to the housings 51 by compressing the coil springs 56.

Extended longitudinally through the central opening of the sleeve 44 of the indexing mechanism 36 is a shaft 57 which is supported for rotation by a bushing 58 arranged within the sleeve 44 and within the shank 48 of the cover plate 47 10 associated with the head 45. The shaft 57 has fixed thereto a bevel gear 59 (Figs. 2 and 4). The bevel gear 59 meshes with similar bevel gears 60, each of which is mounted on the inner end of a coupling 61 which is supported for rotation within a bushing 62 associated with one of the cylindrical housings 51. Each coupling 61 has an opening formed therein which receives the inner end portion of a drill 63, the drill being secured to the coupling by a set screw 64. Also each coupling has associated with it a ball bearing structure 65 which facilitates free rotation thereof. The outer portions of the drills 63 are disposed within the sleeves 54, as shown in Fig. 2, said sleeves being provided with bushings 66 which support the drills for free rotation within the sleeves. Additionally each sleeve 54 is provided with openings 67 located adjacent to its outer end through which shavings may pass during drilling operations.

At points located ninety degrees from the screwthreaded openings 50 which receive the reduced inner end portions of the housings 51, the head 45 is provided with a second pair of opposed and alined screwthreaded openings 68 (Fig. 4). 35 Each of these openings receives the reduced, screwthreaded inner end portion of a rod 69, each of said rods being provided with a cavity 70 formed therein, which is closed at the outer end of the rod by a cap 71 that is screwed on said outer end portion of said rod. The cap 71 of each rod 69 is provided with a central opening through which a sleeve 72 is extended, said sleeves each being provided with a flange 73 which is of only slightly less diameter than the cavity 70 of the 45 associated rod 69. Arranged within each of the cavities 70 is a coil spring 74 which contacts at its opposite ends with the base of the cavity and the flange of the associated sleeve, said coil springs being adapted normally to force the sleeves outwardly to the limits of their outer movement with respect to the rods 69 where the flanges of said sleeves contact with the associated caps 71 as shown in Fig. 4. Each of the rods 69 supports a punch 75 which is provided with a reduced, screwthreaded inner end portion 75' that is screwed in a screwthreaded opening formed in the associated rod, the punches being extended from their points of attachment to the rods 69, through the cavities 70, and through the sleeves 60 72 to points a slight distance beyond the outer ends of the sleeves and the outer end portions of said punches are provided tapered faces 75'.

The sleeve 39 of the supporting member 37 supports at an end thereof a block 76 to which is 65 fixedly attached a bracket 76' (Figs. 1 and 2). This bracket supports an electric motor 57' which is cooperatively associated with the shaft 57 whereby said shaft may be rotated by said motor. The block 76 also supports a stud shaft 77 (Fig. 2) on which a bevel gear 78 is supported for rotation. The bevel gear 78 meshes with a similar bevel gear 79 which is pinned or otherwise secured to a vertical shaft 80 which is supported by an upper bearing portion 81 and a lower bearing 82 75

both of which are parts of the block 76. The upper bearing portion 81 and the lower bearing 82 are provided with bushings 83 in which the vertical shaft 80 rotates. Pinned, or otherwise secured to the vertical shaft 80 between the bearing portion 81 and the bearing 82 is an elongated gear 84 which is arranged in mesh with a pinion 85. The pinion 85 is secured at the upper end of a vertical shaft 86 which is supported for rotation by an upper bearing 87 secured to the guide 33 and a lower bearing 88 which is supported by the bearing 13 previously referred to herein. At the lower end of the vertical shaft 86 a bevel gear 89 is fixed thereto and this bevel gear meshes with a bevel gear 90 which is an integral part of a clutch member 91 that is supported by the reduced portion 11' of the shaft 11. The structure providing the bevel gear 90 and the clutch member 91 is not fixed to the shaft portion 11', but instead said structure is loosely supported on said shaft portion so that during certain phases of the operation of the machine the shaft portion 11' may rotate with respect to the bevel gear 90 and clutch member 91.

25 The shaft portion 11' is supported at its outer end by a bearing 92, and mounted on said shaft portion is a clutch member 93, said clutch member being splined to the shaft portion as indicated at 93' in Fig. 2 so that said clutch member 93 may move longitudinally of the shaft portion into and out of clutching engagement with respect to the clutch member 91. The clutch member 93 is provided with a portion 94 which is of greater diameter than the remainder of the clutch member, and this larger portion is provided with a cam face 94' which contacts with a roller 95 supported by a fixed bracket 96. Additionally the shaft portion 11' has fixedly mounted thereon a brake element 97 (Figs. 2, 5 and 6) which is of segmental shape as shown in Fig. 6. The curved face of the brake element contacts with a strip of brake material 98 which is associated with a member 99, this member being slidably supported for vertical movement on a pair of rods 100 which are fixedly supported by the base plate 5 of the machine. Each of the rods 100 has mounted thereon a nut 101 and an associated washer 101', and located between the washers 101' and the lower face of the member 99 are coil springs 102 which surround said rods. The coil springs 102 are under compression so that they exert upward force against the member 99 so as to force the strip of braking material into close contact with the curved face of the brake element 97 when said curved face of said brake element is in proper position to receive such contact. Also at the upper ends of the rods 100 nuts 103 are mounted thereon to limit upward movement of the member 99. As shown in Figs. 2 and 5 a coil spring 104 is interposed between the brake element 97 and the clutch member 93 and this coil spring tends to move the clutch member 93 toward the clutch member 91.

Secured to the sleeve 44 of which the head 45 forms a part is a disk 105 (Figs. 1, 2, 3, and 4) which is provided with a plurality of radial slots 106. The disk 105 is provided with a central aperture through which the shaft 57 extends loosely so that said shaft and said disk may rotate with respect to each other, and said disk is secured to the sleeve 44 by screws 107. As shown to the best advantage in Fig. 3 there are four of the radial slots 106 in the disk 105, and also said disk is provided with four notches 108 which are located at the peripheral edge of the disk ap-

proximately midway of the ends of the slots at said peripheral edge of the disk. Arranged in association with the disk 105 is a second disk 109 which is secured by screws 109' to the pinion 78 and this second disk has mounted thereon four bolts 110 on which rollers 110' are mounted. The rollers are so positioned on the disk 109 that as said disk is rotated they will successively pass into the slots 106 of the disk 105 and as movement of the disk 109 continues with a roller 109 operating in one of the slots of said disk 105 the disk 105 will be rotated ninety degrees during each operation of a roller 110' in engagement with the walls of a slot 106.

In order to lock the disk 105 against unintended rotation a locking member 111 is provided which is pivoted at its lower end as indicated at 112 to the block 76 and is provided with a coil spring 116 at its upper end. The locking member 111 includes an extension 113 which is adapted to enter the notches 108 of the disk 105 when said disk has been rotated to proper positions where said notches may receive said extension of the locking member. Also the locking member 111 is provided with a roller 114 into contact with which cam faces 115 formed at the peripheral edge of the disk 109 move. It is obvious that as rotation of the disk 109 is started the cam face 115 in contact with the roller 114 will cam said roller outwardly against the force of the coil spring 116, thereby moving the extension 113 out of the notch 108 of the disk 105 into which it projected. A curved portion of the peripheral face of the disk 109, which moves into contact with the roller 114 will hold the extension away from the peripheral edge of the disk 105 and during this period the disk 105 will be rotated ninety degrees by the disk 109 as has been already explained. When such ninety degree rotation of the disk 105 has been completed another of the cam faces 115 will have moved into position adjacent to the roller 114 and also another notch 108 of the disk 105 will have moved into position adjacent to the extension 113 of the locking member 111. The result of this situation will be that the roller will be moved inwardly by the coil spring 116 into contact with the adjacent cam face 115 and the extension 113 will move into the adjacent notch 108 to lock the disk 105.

Each time the machine is stopped after an operation thereof, by the cam 32 separating the clutch members 14 and 10 as has been previously explained herein, the indexing mechanism comes to rest with the upper portion of one of the sleeves 54 and the drill 63 therein extended above the top plate 2 of the main frame of the machine as shown in Fig. 7, said top plate being provided with an aperture 2' through which said sleeve and drill pass. The sleeve so extended above the top plate 27 of the machine serves as a post which temporarily supports a last L on which is arranged a shoe S to be heeled. Lasts, of course, are of different heights and it is necessary therefore to provide a last supporting means which is adjustable so that the heel seat of every lasted shoe to be operated on by the machine is the same distance from the top surface of the top plate 2 regardless of the height of the last. The adjustable means referred to comprises a lower bar 117 which is provided with a slot 118 formed longitudinally therein and open at the forward end of the bar as shown to the best advantage in Fig. 8, and the legs 117' at opposite sides of the slot 118 are provided with inclined cam faces 75

as shown at 119 in Fig. 1. The forward part of the lower bar 117 is set down in a cavity 120 formed in the top plate 2 of the machine, the rear portion of said bar resting on the top surface of the top plate 2.

The last adjusting means includes also an upper member 121 which has a rear portion which is thicker than the forward portion thereof as shown clearly in Fig. 1, said upper member including also a downwardly extended intermediate portion 122, which is disposed between the spaced legs of the lower bar 117, and opposed marginal portions 123 which overlie the legs of the lower bar. The opposed marginal portions 123 of the upper member 121 are provided with inclined lower faces which correspond to the inclined faces at the tops of the legs of the lower bar 117. The upper member is held in non-sliding position by a bolt 124 which passes through an aperture 125 that is formed through a wall 126 of the upper member that is located at the base of a cavity 127 formed in said upper member. The shank of the bolt 124 extends through the cavity 127 as shown in Fig. 9 and a coil spring 128 surrounds said bolt shank and contacts at its upper end with the lower face of the head of the bolt and at its lower end with the top face of the wall 126. The coil spring 128 tends to urge the upper member 121 downwardly so as to maintain the inclined faces of the marginal portions 123 of said upper member in contact with the inclined faces of the spaced legs of the lower bar 117.

The lower bar 117 of the last adjusting means has pivoted thereto an arm 129 which is pivoted at one end at 130 to a shorter arm 131 which is pivoted at 132 to the top plate 2 of the machine. At the opposite end of the arm 129 a connecting element 133 is pivotably attached thereto and this connecting element is attached also to an operating handle 134 which is pivotably attached to a fixed part of the machine at 135 (see Fig. 7). In order to retain the operating handle in positions to which it is adjusted a toothed plate 136 is fixed to the top plate of the machine and teeth formed on the operating handle are adapted to engage the teeth of the plate 136 to lock the operating handle in desired positions.

When a lasted shoe is to be associated with the machine the last is applied to the sleeve 54 which extends through the aperture 2' of the top plate of the machine, when the machine is at rest, this sleeve passing also through an aperture 137 formed through the upper bar 117. At the time a lasted shoe is applied to the machine as described the insole of the shoe is imperforate and the insole will contact the top edge of the sleeve 54. If the last is of the same height as the preceding last the bottom face of the inverted last will contact with the top face of the upper member 121 of the last adjusting means so as to support the last. On the other hand if last being applied to the machine is of less height than the preceding last, the operating handle 134 of the last adjusting means will be drawn forwardly at its upper end to slide the lower bar 117 of the last adjusting means with respect to the upper member 121 of said last adjusting means and, through cooperation of the inclined faces of said lower bar and said upper member of the last adjusting means, raise said upper member to cause its top face to contact with the lower face of the inverted last to support the last. Also if the last being applied to the machine is of

greater height than the preceding last the lower bar of the last adjusting means is moved rearwardly to lower the upper member of said last adjusting means to the proper elevation where it will support the last being applied to the machine.

The improved machine disclosed herein includes a hold-down mechanism which is intended to retain a lasted shoe in its proper position with respect to the machine while a heel 10 is being applied to said shoe, and for maintaining the heel being attached to the shoe in its proper position with respect to the shoe during the heelng operation. The hold-down mechanism comprises a support 138 which is 15 bolted or otherwise secured to the top plate of the machine, and pivoted to said support at 139 is a pair of spaced arms 140. The forward portions of the spaced arms 140 are supported by a toggle structure which is made up of an 20 upper arm 141 and a lower arm 142, said upper and lower arms being pivotably connected together at 143, and the upper arm being provided with an extension 144 which serves as an operating handle for operating the toggle. The 25 lower arm 142 is pivoted at 145 to the spaced arms 140, and the upper arm 141 is pivoted at 146 between the legs of a bifurcated element 147, said bifurcated element being provided with a screwthreaded shank 148 which extends 30 through an opening formed through a front extension 138' of the support 138. The screwthreaded shank 148 has nuts 150 mounted thereon which are screwed into contact with the top and bottom faces of the extension 138' of the 35 support 138, said nuts being adjustable longitudinally of the screwthreaded shank so as to provide for adjusting the bifurcated element 147 vertically. The bifurcated element has a bracket 151 secured to it and said bracket has attached 40 thereto at one end a coil spring 152, the opposite end of the coil spring being connected to a bar 153 fixed to the spaced arms 140.

Pivotably attached to the spaced arms 140 by means of a pivot pin 154 is a member 155, the portion of said member through which the pivot pin 154 extends being located between the forward portions of said spaced arms 140. The member 155 is of substantially inverted L-shaped formation as shown to the best advantage in Fig. 14, including a short substantially horizontal leg 155^a and a longer leg 155^b which is extended at a substantial right angle relative to said short leg. The longer leg of the member 155 has a slot 156 formed therein and adjacent to the 55 lower end of said longer leg pins 157 are extended therefrom on which are mounted cylinders 158 formed of felt or other yieldable material. As shown to the best advantage in Fig. 7 the pins 157 and the cylinders 158 are disposed in divergent relation with respect to each other.

Associated with the longer leg 155^b of the member 155 is a traveling head 159 (Fig. 14) which includes a rear portion 159^a that extends into the slot 156 of the longer leg of the member 155, and is provided with shoulders 159^b at opposite sides of said portion 159^a which contact with the forward face of the longer leg of the member 155 for sliding movement with respect thereto. The traveling head 159 may be adjusted longitudinally of the longer leg of the member 155 by an adjusting screw 160, the screwthreaded shank of which extends through a screwthreaded opening formed through the short leg 155^a of the member 155. The lower end por- 75

tion of the shank of the adjusting screw 160 is connected to the traveling head 159 in such manner that said shank may rotate with respect to the traveling head while being cooperatively connected thereto so that adjustment of the adjusting screw 160 upwardly or downwardly relative to the short leg of the member 155 will impart sliding movement to the traveling head with respect to the longer leg of said member 155. In order to lock the traveling head in positions to which it has been adjusted a bolt 161 is provided. This bolt is extended through the slot 156 in the member 155 and is provided with a head 161^a at one end thereof which is large enough to overlap the opposite sides of the slot, said bolt passing also through an aperture formed through the traveling head and being provided with a nut 161^b mounted on its outer, screw-threaded end portion which is adapted to be forced into close, frictional contact with the forward face of the traveling head. It is obvious that the nut 161^b may be loosened to permit the traveling head to be adjusted after which said nut may be tightened against the forward face of the traveling head to lock said head in its adjusted position. Also, associated with the traveling head 159 is an element 162 which is pivoted at 163 to said traveling head, said element 162 being provided with a flat plate portion 162' which is adapted to contact with the top face of an inverted heel when said heel is being applied to a shoe with the aid of the machine disclosed herein as shown in Fig. 1.

After an inverted lasted shoe has been applied to one of the sleeves 54 extended above the top plate 2 of the machine as previously explained herein, a heel H is arranged in proper association with the lasted shoe. At this time the toggle provided by the arms 141 and 142 is broken forwardly so that the forward end portions of the spaced arms 140 and the parts associated therewith are elevated above the heel by the coil spring 152. The operator of the machine then grasps the outer end portion of the handle 144 and draws same downwardly whereby through operation of the toggle the forward end portions of the spaced arms 140 are likewise moved downwardly. During such downward movement of the forward end portions of the spaced arms 140 the heel engaging mechanism associated therewith is guided by the operator to cause the cylinders 158 to engage the side face of the heel and to bring the flat plate portion 162' of the element 162 into engagement with the top face of the inverted heel H. After contact has been made with the heel by the cylinders 158 and the element 162 downward movement of the handle 144 is continued until the pivot pin 143 moves beyond dead center, at which time the forward end portions of the spaced arms 140 will be locked in their downward position and the cylinders 158 and element 162 will hold the heel H firmly in its proper position with respect to the shoe.

The improved machine disclosed herein includes improved means for feeding heel fastening devices to the punches 75 of the indexing mechanism. This means is shown to the best advantage in Figs. 1, 2, 10, 11, 12, and 13 and said means includes a bracket 165 which is secured to the top plate 2 of the machine at the lower face thereof. The bracket 165 is provided with a downwardly extended plate 165^a in which a slot 165^b is formed, the bracket being provided with webs 165^c which are alined with the opposite sides of the slot. Pivoted to and between the webs

165^c by means of a pivot bolt 166 is an arm 167, said arm being provided with a substantial horizontal shank portion 168 at its upper end which is externally screwthreaded through a portion of its length. The screwthreaded portion of the shank 168 has a nut mounted thereon and interposed between said nut and the bracket 165 is a coil spring 169, said coil spring being adapted to urge the lower portion of the arm 167 in the direction indicated by the arrow in Fig. 2.

Secured to the arm 167 by suitable fastening devices 170^a is a member 170 which in plan view is shaped as shown in Fig. 15; that is to say said member is provided with a portion 170' which contacts directly with the arm 167, and a portion 171 which is disposed with respect to the portion 170' as shown in Fig. 15. The portion 171 of the member 170 is provided with a straight groove 172 formed in its top face and this groove leads to a semicircular notch 173 that is formed at an end of said portion 171. Associated with the member 170 is a pair of jaws 174, said jaws being of substantially L-shaped formation as shown in Fig. 15 and being provided with curved cutout portions 175 which when the jaws are in their normal positions cooperate with each other and with the notch 173 of the portion 171 of the member 170 to provide a circular opening. The jaws 174 are secured to the portion 171 of the member 170 by bolts 176 which extend loosely through apertures formed through said jaws and are screwed into said portion 171 of said member 170, coil springs 177 being arranged about said bolts and being interposed between the jaws and washers associated with the heads of said bolts. Leading to the groove 172 formed in the portion 171 of the member 170 is a hollow conductor 178 which communicates with a hopper 179 (Fig. 1), the hopper being adapted to receive heel fastening devices F of the type shown in Fig. 20 and said heel fastening devices being adapted to pass from the hopper through the hollow conductor with the flanged ends F' of the fastening devices trailing the smaller ends thereof.

Pivoted to the arm 167 by means of a pivot bolt 180 is an element 181 which has formed thereon a pair of opposed wings 182 which are disposed at opposite sides of the arm 167. The element 181 is provided with spaced extensions 183 between which is supported for rotation a roller 184. The arm 167 has an opening 185 formed therethrough which receives a plunger 186 that is provided with a pointed end, said plunger being urged toward the element 181 by a coil spring 187 which is interposed between the inner face of the plunger and the inner face of a screw-threaded plug 188 that is screwed into a screwthreaded portion of the opening 185. The element 181 is shiftable about its pivot 180 to different positions with respect to the arm 167 and said element is provided with depressions 189 into which the pivoted end of the plunger 186 moves to lock said element in the positions to which it is shifted.

During operation of the machine disclosed herein the indexing mechanism 36 is reciprocated vertically because of its connection by the connecting rod 41 to the crank 43 of the shaft 11. Also the head 45 is rotated while the indexing mechanism is in the lower portion of its stroke by operation of the geneva movement which includes the disks 105 and 109, said head describing an arc of ninety degrees each time it is rotated to successively bring a drill 63 and then a punch 75 to a position where the drill or punch so posi-

tioned may pass through the aperture 2' in the top plate 2 of the machine. The pair of drills 63 and the pair of punches are arranged in opposed and alined relation as shown in Figs. 10 and 11 and necessarily when the head 45 moves downwardly to withdraw a punch from the aperture 2' of the top plate 2 after said punch has passed upwardly through the aperture 2', the opposed or lower punch will likewise move downwardly. It is during this downward movement of the lower punch that a heel fastening device F is applied to the lower punch, so that when the punch to which a heel fastening device is applied again reaches the upper position for movement through the aperture 2' of the top plate 2 it will have a heel fastening device supported thereon.

The cover plate 47 of the head 45 of the indexing mechanism 36 has screwthreadedly mounted thereon a cam 190 the outer face 190' of which is so located and formed that the roller 184 associated with the arm 167 while contacting with said cam face 190' will retain the arm 167 against the force of the coil spring 169, in the position in which said arm is shown in Fig. 2. In this position of the arm a heel fastening device F will be discharged from the lower end of the hollow conductor 178 into the circular opening provided by the notch 173 at an end of the portion 171 of the element 170 and the curved cutaway portions 175 of the jaws 174, the flange F' at the upper end of the heel fastening device supporting the device in the circular opening by overlapping portions of the portion 171 of the element 170 and of the jaws 174. In positions adjacent to the locations of the punches the cam 190 is provided with a pair of portions 191 each of which includes a pair of cam faces, one being designated by the reference character 192 and the other by the reference character 193. As the indexing mechanism of the machine moves upwardly at the top of its stroke the roller 184 is so positioned that it will pass into contact with the cam face 193 at the lower end of the cam 190 which will permit the coil spring 169 to swing the lower end of the arm 167 from the position in which it is shown in Fig. 2 to the position said lower end of said arm is shown in Fig. 12. In this latter position the circular opening, provided by the notch 173 formed in the portion 171 of the member 170 and the curved cutaway portions 175 of the jaws 174, is in alinement with the lowermost punch 75. When the indexing mechanism reaches its uppermost position the roller 184 is engaged by a cam face 194, one of which is located adjacent to the cam face 193 of each cam portion 191, and the element 181 is moved on its pivot 180 so as to bring the roller in line with the cam face 192. As has already been explained herein the element 181 is held in its two different positions by the pointed end of the plunger 186 entering tapered depressions in said element, and when the element 181 is moved by the cam face 194 as described the pointed end of the plunger is forced from one of the depressions 189 and when the element reaches its other position the pointed end of the plunger enters the other of said depressions 189.

The element 181 is shifted from a position where the roller is alined with the effective cam face 193 to a position where said roller is alined with the associated cam face 192 at the top of the stroke of the indexing mechanism of the machine and said indexing mechanism immediately starts to move downwardly. This causes the lower end of the lower punch 75 to move into the heel fastening device gripped by the jaws 174 and the

portion 171 of the member 170. When the lower end of the lower punch 75 has moved into the heel fastening element gripped by the jaws 174 the roller 184 contacts with the high portion of the cam face 192. This causes the arm 167 to be moved away from the lower punch as shown in Fig. 13 whereby the heel fastening element F is released from the jaws 174 due to the jaws being spread apart by movement thereof with respect to the heel fastening device as shown in Fig. 15, the loose attachment of the jaws to the member 170 and the coil springs 177 permitting such spreading of the jaws. The arm 167 is moved rearwardly by the cam face 192 until the roller 184 contacts with the flat cam face 190' of the cam 190 as shown in Fig. 2, the indexing mechanism continuing its downward movement to the lower end of its stroke. The heel fastening elements F pass through the hollow conductor 178 with the flanged ends uppermost and when the arm 167 moves from the position in which it is shown in Fig. 2 to the position of said arm shown in Fig. 12 the lowermost heel fastening device in the hollow conductor is supported by the moving base of the groove of the portion 171 of the member 170. When the arm 167 is again returned to the position shown in Fig. 2 the lowermost heel fastening element F in the hollow conductor 178 drops into the circular opening provided by the groove 173 of the member 170 and the cutaway portions 175 of the jaws 174.

In order to insure free movement of the heel fastening devices into the opening provided by the notch 173 of the member 170 and the cutaway portions 175 of the jaws 174 the cam face 190' is provided with cam projections 195 formed thereon one of which moves into contact with the roller 184 each time the arm 167 moves to the position in which it is shown in Fig. 2. When one of the extensions 195 contacts with the roller 184 the arm 167 is subjected to a swaying movement relative to the lower end of the hollow conductor 178 which agitates the lowermost heel fastening element in said hollow conductor and thereby causes it to work its way into the circular opening at the locations of the jaws 174. In order to retain the heel fastening devices F on the punches 75 when said heel fastening devices are applied to said punches as heretofore described herein each punch is provided with an annular groove formed therein in which a split ring 196 formed of spring material is disposed. When a heel fastening device is applied to a punch it is forced over the split ring 196 thereof and the tendency of the split ring to expand against the inside face of the heel fastening device will retain said heel fastening device on the punch.

In the operation of the improved machine disclosed herein the operator thereof applies a lasted shoe to one of the sleeves 54 which is extended through the aperture 2' of the top plate of the machine, one of these sleeves being extended through said aperture 2' each time the machine comes to rest to provide a post that is received in a tube-lined aperture L^a formed through the last L. The last adjusting mechanism of which the operating handle 137 forms a part is then adjusted to properly support the last as has been previously explained, and the hold-down mechanism is operated to draw the cylinders 137 and the element 162 in contact with a heel which has been previously arranged in proper position relative to the heel seat of the shoe. After operation of the hold-down mechanism the lasted shoe with the heel associated therewith is very

securely held in position to be operated on by the machine. The motors 1 and 57 being in operation the operator next actuates the operating element 26 so as to cause the clutch members 10 and 14 to move into clutching engagement thereby causing the motor 7 to rotate the shafts 11 and 20. Rotation of the shaft 11 will cause the indexing mechanism of the machine to be moved upwardly because of the connection of said indexing mechanism to the crank 43 of the shaft 11 by the connecting rod 41, and the upwardly moving rotating drill 63 within the sleeve 54 extended through the aperture 2' in the top plate 2 will drill a hole through the insole S of the lasted shoe and into the heel H as shown in Fig. 16. It is to be noted that when the indexing mechanism moves upwardly to cause the drill 63 to drill a hole through the insole of the shoe and in the heel thereof, the associated sleeve 54 is prevented from moving upwardly because of the contact of the top edge thereof with the insole of the shoe. Such upward movement of the indexing mechanism with respect to the upper sleeve 54 will cause the coil spring 56 (Fig. 2) associated with said upper sleeve to be compressed.

When the indexing mechanism reaches the upper limit of its movement the drill will have completed the drilling operation and the indexing mechanism then starts on its downward movement withdrawing the drill from the hole and eventually withdrawing the drill and its associated sleeve 54 from the aperture formed through the last L. As the indexing mechanism approaches the lower limit of its downward movement the cam face 94' of the clutch member 93 will move into contact with the roller 95 thereby permitting the coil spring 104 to move said clutch member 93 into clutching engagement with the clutch member 91. Because of the clutching engagement of the clutch members 91 and 93 rotary motion will be transmitted from the shaft 11 through the clutch members 91 and 93, bevel gears 89 and 90, shaft 86, gears 85 and 84, shaft 80, and bevel gears 79 and 78 to the disk 109 of a geneva movement, and said disk 109 will transmit rotary movement to the disk 105 of said geneva movement through an arc of ninety degrees. The rotary movement of the disk 105 will impart like movement to the sleeve 44 of the indexing mechanism because of the fact that said disk 105 is secured to said sleeve 44 and such rotation of the sleeve 44 will rotate the head 45 through an arc of ninety degrees, the opposed drills 63, the opposed punches 75, the cam 190 and the other parts carried by the head moving ninety degrees therewith.

The rotation of the head 45 being completed while the indexing mechanism is in the lower portion of its stroke, the indexing mechanism moves upwardly with one of the punches positioned so that it will eventually pass through the aperture 2' of the top plate 2 of the machine, said punch having been so positioned by the previous ninety degree rotation of the head 45. The upper punch which at this time is moving toward the aperture 2' of the top plate 2 has previously had applied thereto one of the heel fastening devices F as has been heretofore explained, and this upper punch moves through the aperture 2' of the top plate 2, through the aperture L' formed through the last L (see Fig. 17) and carries the heel fastening device F supported thereby into the hole drilled through the insole of the shoe and in the heel thereof as shown in Fig. 18. As the upward movement

of the indexing mechanism continues the top edge of the sleeve 72 surrounding the punch 75 forces the flange of the heel fastening element into countersunk relation with respect to the insole S of the shoe on the last L, whereupon upward movement of said sleeve 72 will be arrested and continued upward movement of the indexing mechanism will cause the coil spring 74 associated with the sleeve 72 to be compressed. Continued movement of the indexing mechanism after upward movement of the sleeve 72 is arrested will cause the punch 75 to move against the inner faces of the displaceable portions F' of the heel fastening device and said displaceable portions will be forced by the tapered face adjacent to the end of the punch outwardly to cause them to bite into the material of the heel adjacent to the hole therein as shown in Fig. 19.

When the displaceable portions of the heel fastening device have been forced outwardly into the material of the heel as described the indexing mechanism has again reached the upper limit of its vertical movement and thereupon said indexing mechanism starts downwardly withdrawing the punch from the heel fastening element in the shoe and eventually withdrawing the punch and its associated sleeve 72 from the aperture formed through the last and from the aperture 2' of the top plate 2. As the indexing mechanism continues its downward movement the lower punch receives a heel fastening device F from the mechanism for feeding said heel fastening devices to said punches as already explained herein, and the indexing mechanism continues its downward movement to the lower portion of its downward stroke where said indexing mechanism is again subjected to a rotation of ninety degrees. The indexing mechanism then moves upwardly with a drill 63 and an associated sleeve 54 at the top of the indexing mechanism and in position to be moved through the aperture 2' of the top plate 2 and when said sleeve 54 has passed through said aperture 2' and extends above the top plate 2 of the machine the proper distance the high point 32' of the cam 32 will disconnect the clutch members 14 and 10 to stop the machine. It is to be noted that the shaft 11 makes two revolutions during a complete operation of the machine during which a hole is drilled through the insole and in the heel of the shoe, the heel fastening element is introduced into the hole so drilled, the displaceable portions of the heel fastening device are spread outwardly to cause them to bite into the material of the heel, and the machine is returned to its starting position. During these two revolutions of the shaft 11 the shaft 20 rotates but once and when the single rotation of said shaft 20 is completed the high spot 32' of the cam 32 disconnects the clutch members 14 and 10 to halt operation of the machine.

The brake element 97 coacting with the element 99 serves to control operation of the shaft 11 so as to eliminate jerky operation of the machine caused by the weight of the reciprocating indexing mechanism. To further insure smooth operation of the machine a flexible element 197 is attached to a bracket 197' which is secured to the block 76 (Fig. 1), said flexible element passing over a pulley 198 (Fig. 7) and having a weight 199 suspended therefrom. The weight 199 has a coil spring 200 attached thereto, said coil spring also being attached to the base plate of the machine and said weight and coil spring serving to

counterbalance the weight of the indexing mechanism.

We claim:

1. A machine for attaching heels to shoes with the aid of fastening devices having displaceable portions adapted to be forced into the material of the heels, comprising a rotary member, a drill supported by said rotary member, a punch supported by said rotary member, means for subjecting said rotary member to intermittent rotary movement so as to bring said drill to a position where it may be operated to drill a hole through the insole and in the heel of a shoe associated with the machine and then bring said punch to a position where it may be operated to force the displaceable portions of a heel fastening device introduced into the hole so drilled into the material of the heel adjacent to the hole therein, and means for rotating said drill.
2. A machine for attaching heels to shoes with the aid of fastening devices having displaceable portions adapted to be forced into the material of the heels, comprising a rotary member, a drill supported by said rotary member, a punch supported by said rotary member, a sleeve arranged to embrace said punch and adapted for movement longitudinally with respect thereto, means for subjecting said rotary member to intermittent rotary movement so as to bring said drill to a position where it may be operated to drill a hole through the insole and in the heel of a shoe associated with the machine and then bring said punch to a position where said sleeve may introduce a heel fastening device in the hole so drilled and said punch may be operated to force the displaceable portions of said fastening device into the material of the heel adjacent to the hole therein, and means for rotating said drill.
3. A machine for attaching heels to shoes with the aid of fastening devices having displaceable portions adapted to be forced into the material of the heels, comprising a rotary member, a drill supported by said rotary member, a sleeve arranged to embrace said drill and adapted for movement longitudinally with respect thereto, a punch supported by said rotary member, a sleeve arranged to embrace said punch and adapted for movement longitudinally with respect thereto, means for subjecting said rotary member to intermittent rotary movement so as to bring said drill to a position where it may be operated to drill a hole through the insole and in the heel of a shoe associated with the machine and then bring said punch and its associated sleeve to a position where said sleeve may introduce a heel fastening device in the hole so drilled and said punch may be operated to force the displaceable portions of said fastening device into the material of the heel adjacent to the hole therein, and means for rotating said drill.
4. A machine for attaching heels to shoes with the aid of fastening devices having displaceable portions adapted to be forced into the material of the heels, comprising a rotary member, a drill supported by said rotary member, a sleeve arranged to embrace said drill and adapted for movement longitudinally with respect thereto, a punch supported by said rotary member, a sleeve arranged to embrace said punch and adapted for movement longitudinally with respect thereto, means for subjecting said rotary member to intermittent rotary movement so as to bring said drill to a position where it may be operated to drill a hole through the insole and in the heel of a shoe associated with the machine and then bring said punch through the insole and in the heel of a shoe associated with the machine and then bring said punch to a position where it may be operated to force the displaceable portions of said fastening device into the material of the heel adjacent to the hole therein, and means for rotating said drill.
5. A machine for attaching heels to shoes with the aid of fastening devices having displaceable portions adapted to be forced into the material of the heels, comprising a rotary member, means for supporting said rotary member for reciprocating movement, a drill supported by said rotary member, a punch supported by said rotary member, means for subjecting said rotary member to intermittent rotary movement so as to bring said drill to a position where it may be operated to drill a hole through the insole and in the heel of a shoe associated with the machine and then bring said punch to a position where it may be operated to force the displaceable portions of a heel fastening device introduced into the hole so drilled into the material of the heel adjacent to the hole therein, means for rotating said drill, and means for subjecting said rotary member to reciprocating movement to cause said drill and punch to perform their drilling and fastener portion displacing operations.
6. A machine for attaching heels to shoes with the aid of fastening devices having displaceable portions adapted to be forced into the material of the heels, comprising a rotary member, means for supporting said rotary member for reciprocating movement, a drill supported by said rotary member, a punch supported by said rotary member, a sleeve arranged to embrace said punch and adapted for movement longitudinally with respect thereto, means for subjecting said rotary member to intermittent rotary movement so as to bring said drill to a position where it may be operated to drill a hole through the insole and in the heel of a shoe associated with the machine and bring said punch and its associated sleeve to a position where said sleeve may introduce a heel fastening device in the hole so drilled and said punch may be operated to force the displaceable portions of said fastening device into the material of the heel adjacent to the hole therein, means for rotating said drill, and means for subjecting said rotary member to reciprocating movement to cause said drill, sleeve, and punch to perform their drilling, fastener introducing, and fastener portion displacing operations.
7. A machine for attaching heels to shoes with the aid of fastening devices having displaceable portions adapted to be forced into the material of the heels, comprising a rotary member, means for supporting said rotary member for reciprocating movement, a drill supported by said rotary member, a tubular element arranged to embrace said drill and adapted for movement longitudinally with respect thereto, a punch supported by said rotary member, a sleeve arranged to embrace said punch and adapted for movement longitudinally with respect thereto, means for subjecting said rotary member to intermittent rotary movement so as to bring said drill to a position where it may be operated to drill a hole through the insole and in the heel of a shoe associated with the machine and then bring said punch to a position where it may be operated to force the displaceable portions of said fastening device into the material of the heel adjacent to the hole therein, means for rotating said drill, and means for subjecting said rotary member to reciprocating movement to cause said drill, sleeve, and punch to perform their drilling, fastener introducing, and fastener portion displacing operations.

- with the machine and bring said punch and its associated sleeve to a position where said sleeve may introduce a heel fastening device in the hole so drilled and said punch may be operated to force the displaceable portions of said fastening device into the material of the heel adjacent to the hole therein, means for rotating said drill, and means for subjecting said rotary member to reciprocatory movement to cause said drill, sleeve, and punch to perform their drilling, fastener introducing, and fastener portion displacing operations.
8. A machine for attaching heels to shoes with the aid of fastening devices having displaceable portions adapted to be forced into the material of the heels, comprising a rotary member, means for supporting said rotary member for reciprocatory movement, a drill supported by said rotary member, a tubular element arranged to embrace said drill and adapted for movement longitudinally with respect thereto, a punch supported by said rotary member, a sleeve arranged to embrace said punch and adapted for movement longitudinally with respect thereto, spring elements cooperating with said tubular element and said sleeve which tend to move said tubular element and said sleeve longitudinally of said drill and said punch, means for subjecting said rotary member to intermittent rotary movement so as to bring said drill to a position where it may be operated to drill a hole through the insole and in the heel of a shoe associated with the machine and bring said punch and its associated sleeve to a position where said sleeve may introduce a heel fastening device in the hole so drilled and said punch may be operated to force the displaceable portions of said fastening device into the material of the heel adjacent to the hole therein, means for rotating said drill, and means for subjecting said rotary member to reciprocatory movement to cause said drill, sleeve, and punch to perform their drilling, fastener introducing, and fastener portion displacing operations.
9. A machine for attaching heels to shoes with the aid of fastening devices having displaceable portions adapted to be forced into the material of the heels, comprising a rotary member, means for supporting said rotary member for reciprocatory movement, a drill supported by said rotary member, a punch supported by said rotary member, a sleeve arranged to embrace said punch and adapted for movement longitudinally with respect thereto, means for subjecting said rotary member to intermittent rotary movement so as to bring said drill to a position where it may be operated to drill a hole through the insole and in the heel of a shoe associated with the machine and bring said punch and its associated sleeve to a position where said sleeve may introduce a heel fastening device in the hole so drilled and said punch may be operated to force the displaceable portions of said fastening device into the material of the heel adjacent to the hole therein, means for rotating said drill, and means for subjecting said rotary member to reciprocatory movement to cause said drill, sleeve, and punch to perform their drilling, fastener introducing, and fastener portion displacing operations, and means supported for reciprocatory movement with said rotary member for rotating said drill.
10. A machine for attaching heels to shoes with the aid of fastening devices having displaceable portions adapted to be forced into the material of the heels, comprising a rotary member, means for supporting said rotary member for reciproc-

catory movement, a drill supported by said rotary member, a punch supported by said rotary member, a sleeve arranged to embrace said punch and adapted for movement longitudinally with respect thereto, means for subjecting said rotary member to intermittent rotary movement so as to bring said drill to a position where it may be operated to drill a hole through the insole and in the heel of a shoe associated with the machine and bring said punch and its associated sleeve to a position where said sleeve may introduce a heel fastening device in the hole so drilled and said punch may be operated to force the displaceable portions of said fastening device into the material of the heel adjacent to the hole therein, means for rotating said drill, means for subjecting said rotary member to reciprocatory movement to cause said drill, sleeve, and punch to perform their drilling, fastener introducing, and fastener portion displacing operations, and means comprising an electric motor supported for reciprocatory movement with said rotary member for rotating said drill.

11. A machine for attaching heels to shoes including an element for supporting a last on which a shoe to be operated on by the machine is arranged, a member for adjusting said last-supporting element vertically of the machine to compensate for lasts of different heights, said member being supported for sliding movement relative to said element and said member and element being provided with cooperating inclined faces, means including a resilient element for retaining said last-supporting element against sliding movement when said member is moved with respect thereto and for maintaining said inclined faces in close contact with each other, a hold-down mechanism for holding a last and a shoe thereon with respect to said last-supporting element and for retaining a heel in position with respect to said shoe during operation of the machine, and means for attaching said heel to said shoe.

12. A machine for attaching heels to shoes including an element for supporting a last on which a shoe to be operated on by the machine is arranged, a member for adjusting said last-supporting element vertically of the machine to compensate for lasts of different heights, said member being supported for sliding movement relative to said element and said member and element being provided with cooperating inclined faces, means including a bolt and a coil spring arranged in embracing relation with respect thereto for retaining said last-supporting element against sliding movement when said member is moved with respect thereto and for maintaining said inclined faces in close contact with each other, a hold-down mechanism for holding a last and a shoe thereon with respect to said last-supporting element and for retaining a heel in position with respect to said shoe during operation of the machine, and means for attaching said heel to said shoe.

13. A machine for attaching heels to shoes with the aid of tubular fastening devices having displaceable portions adapted to be forced into the material of the heels, comprising a rotary member, means for supporting said rotary member for reciprocatory movement, a drill supported by said rotary member, a punch supported by said rotary member, means for subjecting said rotary member to intermittent rotary movement so as to bring said drill to a position where it may be operated to drill a hole through the insole and in the heel of a shoe associated with the machine and

then bring said punch to a position where it may be operated to force the displaceable portions of a heel fastening device introduced into the hole so drilled into the material of the heel adjacent to the hole therein, means for rotating said drill, means for subjecting said rotary member to reciprocatory movement to cause said drill and punch to perform their drilling and fastener portion displacing operations, and means for feeding 10 heel fastening devices to said punch.

14. A machine for attaching heels to shoes with the aid of tubular fastening devices having displaceable portions adapted to be forced into the material of the heels, comprising a rotary member, means for supporting said rotary member for reciprocatory movement, a drill supported by said rotary member, a punch supported by said rotary member, means for subjecting said rotary member to intermittent rotary movement so as to bring said drill to a position where it may be operated to drill a hole through the insole and in the heel of a shoe associated with the machine and then bring said punch to a position where it may be operated to force the displaceable portions 20 of a heel fastening device introduced into the hole so drilled into the material of the heel adjacent to the hole therein, means for rotating said drill, means for subjecting said rotary member to reciprocatory movement to cause said drill and punch to perform their drilling and fastener portion displacing operations, and means for feeding heel fastening devices to said punch, said fastener feeding means including a movable element having jaws adapted 30 to receive a fastening device, means for moving said movable element from a position where the jaws thereof receive a fastening device from a fastener supply means to a position where said punch may move into the fastening device held by said jaws, and means for moving said movable element so as to disengage the jaws thereof from the fastening device while said punch is extended into said fastening device.

15. A machine for attaching heels to shoes with the aid of tubular fastening devices having displaceable portions adapted to be forced into the material of the heels, comprising a rotary member, means for supporting said rotary member for reciprocatory movement, a drill supported by said rotary member, a punch supported by said rotary member, means for subjecting said rotary member to intermittent rotary movement so as to bring said drill to a position where it may be operated to drill a hole through the insole and in the heel of a shoe associated with the machine and then bring said punch to a position where it may be operated to force the displaceable portions 40 of a heel fastening device introduced into the hole so drilled into the material of the heel adjacent to the hole therein, means for rotating said drill, means for subjecting said rotary member to reciprocatory movement to cause said drill and punch to perform their drilling and fastener portion displacing operations, and means for feeding heel fastening devices to said punch, said fastener feeding means including a movable element having jaws which receive a fastening device from fastener supply means, and means for moving said movable element to position the fastening device held by said jaws so that said fastening device may be received by said punch during a portion of the reciprocatory movement of said rotary member and said punch.

16. A machine for attaching heels to shoes with the aid of tubular fastening devices having displaceable portions adapted to be forced into the material of the heels, comprising a rotary member, means for supporting said rotary member for reciprocatory movement, a drill supported by said rotary member, a punch supported by said rotary member, means for subjecting said rotary member to intermittent rotary movement so as to bring said drill to a position where it may be operated to drill a hole through the insole and in the heel of a shoe associated with the machine and then bring said punch to a position where it may be operated to force the displaceable portions of a heel fastening device introduced into the hole so drilled into the material of the heel adjacent to the hole therein, means for rotating said drill, means for subjecting said rotary member to reciprocatory movement to cause said drill and punch to perform their drilling and fastener portion displacing operations, and means for feeding heel fastening devices to said punch, said fastener feeding means including a movable element having jaws adapted to receive a fastening device, means for moving said movable element from a position where the jaws thereof receive a fastening device from a fastener supply means to a position where said punch may move into the fastening device held by said jaws, and means for moving said movable element so as to disengage the jaws thereof from the fastening device while said punch is extended into said fastening device.

17. A machine for attaching heels to shoes with the aid of tubular fastening devices having displaceable portions adapted to be forced into the material of the heels, comprising a rotary member, means for supporting said rotary member for reciprocatory movement, a drill supported by said rotary member, a punch supported by said rotary member, means for subjecting said rotary member to intermittent rotary movement so as to bring said drill to a position where it may be operated to drill a hole through the insole and in the heel of a shoe associated with the machine and then bring said punch to a position where it may be operated to force the displaceable portions of a heel fastening device introduced into the hole so drilled into the material of the heel adjacent to the hole therein, means for rotating said drill, means for subjecting said rotary member to reciprocatory movement to cause said drill and punch to perform their drilling and fastener portion displacing operations, and means for feeding heel fastening devices to said punch, said fastener feeding means including a movable element having jaws adapted to receive a fastening device, means for moving said movable element from a position where the jaws thereof receive a fastening device from a fastener supply means to a position where said punch may move into the fastening device held by said jaws, and cam means for moving said movable element so as to disengage the jaws thereof from the fastening device while said punch is extended into said fastening device.
